UNITED STATES PATENT OFFICE.

HERMAN C. PRIEBE, OF BLUE ISLAND, ILLINOIS.

CAR-UNCOUPLING MECHANISM.

Application filed March 9, 1921. Serial No. 451,010.

To all whom it may concern:

Be it known that I, HERMAN C. PRIEBE, a citizen of the United States, residing at Blue Island, in the county of Cook and State of Illinois, have invented a certain new and useful Improvement in Car-Uncoupling Mechanism, of which the following is a full, clear, concise, and exact description.

10 My invention relates to mechanism for uncoupling or separating the knuckles of couplers which are employed to join railway cars into trains.

The invention has for its object the provision of a single piece lever in direct withdrawing engagement with the coupler lock of a car coupler. These single piece levers are devoid of joints and connections which have hitherto been employed in levers that 20 were used to withdraw coupler locks. Owing to the joints and connections that have hitherto been employed in coupler lock withdrawing levers, such levers have been liable to breakage and misadjustment, and have 25 been faulty and unreliable in action.

I will explain my invention more fully by reference to the accompanying drawing showing the preferred embodiment thereof and in which Fig. 1 is a plan view showing 30 an end portion of a car equipped with the device of my invention, the uncoupling position of the parts being shown in dotted lines; Fig. 2 is a view in elevation of the parts shown in Fig. 1, the uncoupling positions of the parts being also here shown in dotted lines; and Fig. 3 is a perspective view of the structure as it appears in full lines in Figs. 1 and 2.

Like parts are indicated by similar characters of reference throughout the different figures.

The drawing shows part of an underframe and the portion of an end sill 1 included in such underframe which may be of 45 any usual or suitable construction. Said end sill carries a bracket 2 near one end thereof, an eye 3 being formed in the upper end of said bracket. This eye serves as a loose bearing for the shank 4 of the lever, 50 this shank carrying a handle 5 at the outer end thereof and a crank 6 at its inner end, this crank being connected with the stem 4 by an arm 7. The crank passes loosely through the eye 8 of any usual or suitable 55 knuckle lock 9 carried by the coupler knuckle 10 and serving to connect this coupler

knuckle with a complementary coupler knuckle upon the next car. The lever structure 4, 5, 6, 7 is a one piece structure, being preferably formed of heavy rod cut to proper length and thereafter bent in suitable shape. To guard against the disassembly of the coupler lock 9 and the crank 6, this crank is desirably angularly extended as indicated at 11. The portion of the coupler lock 9

carrying the eye 8 is in the nature of a vertically movable pin. In order that the lever may operate upon the pin to move it vertically without binding the pin in the knuckle structure that holds it, the lever shank

70 4 is provided with a floating bearing 12 adjacent the crank arm 7, the lever shank passing loosely through this bearing. Said bearing is desirably carried upon one end of an arm 13 whose other end is so pivotally connected at 14 upon the adjacent bumper block 15 as to permit said arm to swing horizontally. The coupler lock is located 75 between the ends of said arm as is also the crank member 6 of the lever. When the uncoupling operation is to be performed the

handle 5 is turned from its normal depending vertical position shown in full lines in the drawing to a horizontal position. Due to this movement of the lever the coupler

80 lock 9 is elevated but as this coupler lock is confined substantially to a straight line vertical movement such lock will force the crank member 6 of the lever to move also in a substantially vertical line thereby causing the lever to swing in the loose bearing

85 3 while it is turning. The lever, in swinging, will carry with it its support or bearing 12 upon which the inner end of the lever shank 4 turns in order to raise the knuckle

90 lock. The horizontally swinging arm 13 is the device upon which the inner portion of the lever structure is supported in a manner to permit the lever to swing or shift 100 while it is being turned. The lever rod is journaled upon the horizontally swinging arm at a point substantially fixed with respect to the arm, whereby the arm need not be slotted where the rod passes therethrough.

The fulcrum for the arm and the fixed relation of the arm and the bearing for the rod afforded by the arm defines a fixed path of movement for the inner end of the rod and a positive movement of the coupling pin or

105 lock to prevent binding action thereof.

110 While I have herein shown and particularly described the preferred embodiment

of my invention I do not wish to be limited to the precise details of construction shown as changes may readily be made without departing from the spirit of my invention, but having thus described my invention I claim as new and desire to secure by Letters Patent the following:—

The combination with the lock of a car coupler; of a lever in the form of a rod ¹⁰ journaled at its outer end and bent at its inner end to form a crank which has with-

drawn engagement with said lock; and a horizontally swinging arm upon which the inner portion of said lever is journaled at a substantially fixed point with reference to ¹⁵ the arm and serving to permit shifting of the lever as it is operated to withdraw the lock.

In witness whereof, I hereunto subscribe my name this twenty-fourth day of February A. D., 1921.

HERMAN C. PRIEBE.
